UNITED STATES PATENT OFFICE.

WILLIAM W. ATKINSON, OF CHICAGO, ILLINOIS.

EXTENSIBLE STRUCTURE.

SPECIFICATION forming part of Letters Patent No. 357,444, dated February 8, 1887.

Application filed November 9, 1885. Serial No. 182,244. (No model.)

To all whom it may concern:

Be it known that I, WILLIAM W. ATKINSON, of Chicago, in the county of Cook, and in the State of Illinois, have invented certain new and useful Improvements in Extensible Structures; and I do hereby declare that the following is a full, clear, and exact description thereof.

My invention relates to extensible structures for use in scaffolding, fire-escapes, &c., as will be hereinafter described.

In the drawings, Figure 1 represents a perspective view of my structure partly extended; Fig. 2, a similar view showing my structure fully extended; Fig. 3, a detail view of the structure and base-connection.

A is the base of my device, which may either rest directly upon the ground or may form part of a truck, and upon this base the lower or horizontal member, B, of my device rests. To the base A is hinged the lower end of a member, C, the means employed for this connection being preferably a swiveled hinge-joint, a.

D is a member hinged or pivoted at one end to the member B, and exactly midway of its length the member D is pivoted to the member C at a point that is distant one-third of the latter's length from the hinged end, the other end of said member D being pivoted to a member, E, and this latter member is pivoted at b to another member, F, on the same vertical line as the pivotal connection of the members C and D. This member F is pivotally connected at c to the member C on the vertical line with pivotal connection of the members B and D, while at d on the same line pivotal connection is established between the member E and another member, G, the latter being also pivotally connected at its lower end to the upper end of the member C, as shown at e, and so on, the members being duplicated from this point, according to the length of the structure required, the pivotal points being equidistant from each other, so that the entire series of

members or levers thus united form quadrilaterals. The lower or horizontal member, B, lies flat upon the base A, and has free movement thereon, so as to permit the lower end of the member D to approach the lower end of the one, C, as the structure is extended. To the base A is preferably secured a wind-

lass, H, for a rope or cable, I, which is passed from thence over a pivotally-hung pulley, g, on the lower end of the member F, and then over a similar pulley on the lower end of the member E, then back over another pulley on the lower end of the member G, and so on back and forth over other pulleys secured to the lower ends of the respective members of the entire structure until the upper limit is reached, and at this point said rope or cable is made fast, so that by operating the windlass H said rope or cable is wound up thereon, thus causing the structure to be rapidly elevated to any desirable height. The windlass H is provided with a pawl and ratchet, f, so as to automatically secure the structure at any height to which it may be elevated, and by further winding of the windlass after the structure is entirely extended the slack of the rope or cable I is thus entirely taken up.

The several members above the one, B, are composed, respectively, of two sections, which are laid one upon the other in such a manner as to form shoulders h, and when the structure is fully extended the shoulder of one section abuts against those adjacent thereto both above and below, and thereby braces said structure and compensate for any strain that may be brought thereon.

To each of the several members, I prefer to unite a rail, K, by means of rounds i, so as to form a short ladder, which, when the structure is entirely extended, will together form a perfectly straight continuous double ladder, extending from the base A upward; but when the structure is only partly extended these short ladders form an angular ascent, so that a desired elevation may be readily reached by climbing one of said short ladders, then changing to another, and so on to the limit of the structure's extension.

It is obvious that I may unite the rails K to the respective members of the frames on one side only of the structure, and thus form a single continuous ladder, when said structure is fully extended, without departing from the spirit of my invention.

At any point or points of the structure deemed desirable I secure eyes k, which serve as means for securing grappling irons or braces adapted to connect said structure with a build-

ing or other support; or these eyes may be employed as a means for connecting an auxiliary ladder, so that the latter may be variously used without interfering with parties engaged upon the main ladder formed by the extension of the structure. In cases where the structure may be used by firemen this means of connecting an auxiliary ladder will be found of great utility, as the latter may be employed to reach one elevation by one set of men without in any way interfering with the operation of another set using the extended structure to reach a great altitude. By the pivotal relative arrangement of the several members of the structure a lever system is produced, whereby an operator standing upon the structure when in its collapsed position can by drawing on the rope or cable I extend the structure and raise himself to any elevation within its limit. If preferred, the windlass mechanism for extending the structure may be placed on the upper portion thereof, instead of at the base, thereby aiding the operator in extending said structure and raising himself therewith.

If desired, a staging can be formed at any point or points of the structure when partially extended by placing boards upon the rounds of opposing ladders. The structure may be provided with pins or other suitable means to unite the several members when said structure is either partially or entirely extended, so as to lock and retain it in such a position independent of the hoisting rope or cable, thereby removing the strain from the latter.

Having thus fully described my invention, what I claim as new, and desire to secure by Letters Patent, is—

1. An extensible structure consisting of a series of pivotally-connected quadrilateral lever-frames, each having its members offset to form shoulders, in combination with means, substantially as described, for extending and collapsing said structure, as set forth.
2. An extensible structure consisting of a series of pivotally-connected quadrilateral lever-frames, each having its several members composed of two sections secured one upon the other in such a manner as to form shoulders, in combination with means, substantially as described, for extending and collapsing said structure, as set forth.

3. An extensible structure consisting of pivotally-connected quadrilateral lever-frames, each having its members offset to form shoulders, in combination with means, substantially as described, for extending and collapsing said structure, as set forth.

4. An extensible structure consisting of a series of pivotally-connected quadrilateral lever-frames, in combination with means, substantially as described, for extending and collapsing the structure, and a series of rails connected by rounds to the respective members of the frames on one side of the structure, whereby a single continuous ladder is formed when said structure is fully extended, as set forth.

5. An extensible structure consisting of a series of pivotally-connected quadrilateral lever-frames, in combination with means, substantially as described, for extending and collapsing the structure, and a series of rails alternately connected by rounds to a portion of the respective members of the frames on both sides of the structure, whereby a double-inclined reversing ascent and descent is formed when said structure is partially extended, as set forth.

6. An extensible structure consisting of a series of pivotally-connected quadrilateral lever-frames having the respective members thereof offset to form shoulders, and provided at each end with a pulley, in combination with a cable secured at one terminus of the structure and passed over the several pulleys thereon, and a windlass mechanism for operating said cable, as set forth.

In testimony that I claim the foregoing I have hereunto set my hand, at Milwaukee, in the county of Milwaukee and State of Wisconsin, in the presence of two witnesses.

WILLIAM W. ATKINSON.
